UNITED STATES PATENT OFFICE

2,196,536

MEANS FOR GASIFYING LIQUID FUELS

Enoch Rector, Flint, Mich.

Application May 10, 1937, Serial No. 141,631

14 Claims. (CL. 48—144)

This invention relates to an improved apparatus for converting liquid fuel into highly combustible fixed gases and more particularly to an apparatus for converting liquid hydrocarbons, such as distillates, fuel oil and the like, into combustible, fixed gases adapted for the operation of internal combustion engines, furnaces and other domestic and industrial purposes. This application relates to an apparatus for utilizing the method of my prior applications Serial No. 690,427, filed September 21, 1933, and Serial No. 54,377 filed December 14, 1935, and issued May 11, 1937, as Patent No. 2,079,632.

It is an object of the invention to provide an improved apparatus for converting non-readily volatilized hydrocarbons into volatile and highly combustible, fixed gases, substantially free of uncombined carbon.

Another object is to provide an improved apparatus for converting liquid fuels into fixed gases and embodying means for utilizing a more volatile fuel when the apparatus is started cold and until it reaches such a temperature as to permit efficient operation on a heavier fuel.

Another object is to provide such an apparatus with new and improved means for changing from one fuel to another so that when a change-over is made the last selected fuel is conveyed substantially directly to the fuel consuming parts of the apparatus.

Another object of the invention is to provide an apparatus whereby liquid fuels may be converted into highly combustible, fixed gases quickly, efficiently and economically.

Further objects include the provision, in a new and improved apparatus wherein a portion of the fuel is burned to supply heat for the conversion of the remainder of the fuel, of means for burning a portion of the fuel and then adding a quantity of air to the products of combustion before they are intermixed with the main portion of the fuel to be gasified; of means for preheating the air and fuel which is burned to provide hot inert gases; of means for cooling the fixed gases prior to their discharge from the apparatus; and, of means for retrieving any fuel which has not gasified, and insuring its gasification.

Other objects and advantages will become readily apparent from the following detailed description taken in connection with the accompanying drawings, in which:

Fig. 1 is a vertical central section through a preferred form of the invention.

Fig. 2 is a horizontal section approximately along the line 2—2 of Fig. 1.

Fig. 3 is a horizontal section approximately along the line 3—3 of Fig. 1.

Fig. 4 is a fragmentary section along the line 5—4 of Fig. 5.

Fig. 5 is a horizontal section approximately along the line 5—5 of Fig. 1.

Fig. 6 is a fragmentary plan view, partly in section on line 6 of Fig. 1. 10

Fig. 7 is a fragmentary section along line 7—7 of Fig. 1.

Fig. 8 is an elevation.

Fig. 9 is a central section through the two-fuel valve, showing the valve in the position for feeding gasoline to the converter. 15

Fig. 10 is an end elevation of the valve.

While a preferred form of the invention has been illustrated in the drawings and shall hereinafter be described in detail, it is not intended to limit the invention to the particular form and arrangement shown, it being contemplated that various changes may be made by those skilled in the art without departing from the spirit and scope of the appended claims. 20 25

In the form shown, the invention comprises generally a main body member 10, a converter casing 11 bolted to one side of the body member, and a fuel bowl 12 mounted on top of the converter casing. The body member 10 is somewhat similar to the main body of a carburetor and is adapted to be positioned vertically as shown with its lower end 10' connected to the intake manifold (not shown) of an internal combustion engine by means including bolt-receiving flanges 13. This member, as illustrated in Fig. 1, has a main downdraft air passage 14 extending therethrough and adjacent its lower end 10' has a disk-like throttle valve 15 mounted on a horizontal shaft 16 and operable by means of an arm 17 provided with a control wire attaching device 18. A cover element 19 is secured to the top of the body member 10 by means of bolts 20 and has a tubular portion 19', a part of which extends upwardly to form an air intake, and part of which extends downwardly into the passage 14 and has an inclined lower edge 21 which forms a seat for an air valve or compensator 22, the construction and operation of which will be described more fully hereinafter. 30 35 40 45 50

The invention contemplates the provision of means for converting the larger portion of the fuel into a gas by subjecting such fuel to the high degree of heat in the products of combustion resulting from burning a small quantity of 55

55

the same fuel. Preferably the inert gases resulting from the complete combustion of the relatively small quantity of fuel are first mixed with a limited amount of atmospheric air so that this air will also be heated before admixture with the larger quantity of fuel, the atmospheric air thus mixed with the inert gases being merely sufficient to support combustion of the lighter portions of the main fuel. To accomplish this, fuel from the bowl 12 is divided into two streams, a small one of which is initially mixed with sufficient air (preferably preheated) so that when burned with said air complete combustion will take place, and the second of which is fed into a mixture of the hot inert gases resulting from such combustion and a regulated amount of air. Thus, as illustrated in Fig. 1, the fuel bowl 12 has a lower portion 12' forming a cover for the converter casing 11 and has an upstanding tubular part 25 extending above the normal fuel level in the bowl. A fuel conveying tube 26 is positioned within the bore 27 of the tubular portion 25 and is threaded at its upper end for engagement with corresponding threads 28 on the tubular portion 25. Adjacent its lower end the fuel tube 26 has a shoulder 28 between which and the adjacent surface of the cover portion 12' a suitable gasket 29 is positioned, thus leaving an annular port intermediate the fuel tube and the fuel bowl. A plurality of holes 26' are preferably drilled vertically through the threads on the fuel tube 26 and tubular portion 25, as illustrated most clearly in Fig. 7 so as to permit fuel to pass downwardly therethrough 35 and into the annular port 27' formed between the fuel tube and the bore 27.

The fuel converter comprises generally a flame chamber FC formed intermediate a plate 30 and a cup-shaped member 31 having a top flange 32 abutting the plate 30, a gasifying chamber GC formed principally in a tubular member 33 secured in the lower portion of the cup 31, and an exit passage from the chamber GC comprising a port or passage 34 between the cup-shaped member 31 and a second surrounding cup-shaped member 35, ports 37 in the member 35 and passages 38 intermediate the member 35 and the converter casing 11. A discharge port 39 in the wall of the casing 11 establishes communication between the passages 38 and a tubular discharge member 40 which extends into the main passage 14 of the body member 10 and has a downwardly directed opening 41. A plurality of ribs 35' (Fig. 5) are preferably provided on the inner surface of the casing 11 along the vertical side wall thereof so as to provide a plurality of cooling passages 38. 11" is a drain plug.

The flame chamber FC has an annular bottom plate 42 from which a plurality of burner tubes 43 extend. Means is provided for supplying these burner tubes with a mixture of fuel or fuel vapor and air, this means herein being disclosed as comprising a fuel supply tube 44 (Figs. 1 and 5) fed from the annular port 27' by means of a horizontal port 45 (Fig. 1), a connecting port 46 and a jet 47. The tube 44 passes downwardly through the flame chamber, (so as to be heated thereby) through the bottom plate 42 of the flame chamber and into a lower annular plate 50. Fuel fed from the jet 47 and through the fuel tube 44 passes into an annular mixing chamber 51 located between the annular plate 50 and a lower annular plate 52. Air is supplied to this chamber by means of an air tube 53 which is secured at its upper end in the cover

12' and extends downwardly through the flame chamber (wherein it is heated) and then downwardly through suitable openings in the plates 30, 42, 50 and 52 so as to discharge heated air into an annular chamber 54 formed in the lower portion of the cup 31 below the plate 52. Air from the tube 53 passes annularly through the chamber 54 and up through a port 55 which is aligned with the fuel tube 44 so that the upwardly moving heated air passing into the chamber 51 mixes with the downwardly moving heated fuel vapor passing into the chamber 51, the mixture of fuel and air passing annularly around the chamber 51, up through a plurality of ports 56 (Figs. 1 and 2) in the plate 50, thence annularly in the chamber 50' (formed between plates 42 and 50) and passes out of the burner tubes 43 (Fig. 5).

The air for the combustion of the fuel in the flame chamber FC is preferably diverted from the air passing into the intake 19' so that the air used for converting the fuel will also be cleaned by the usual air cleaner (not shown) mounted on the intake 19'. As illustrated herein a portion of the air from the intake 19' is diverted by means of an inclined tube 60 which extends into the intake 19' and connects with a vertical passage 61 formed in the body member 10. This air then passes through a port 62 in the body member and into an air chamber 63 formed in the hollow cover 12' above the plate 30. The air tube 63 is provided with a plurality of air inlet ports 64 within this air chamber, so that a portion of the diverted air passes into the air tube 63. These inlet ports are so proportioned that the air passing therethrough is just sufficient to cause complete combustion of the flame fuel fed through the jet 47.

An additional quantity of air supplied to the air chamber 63 passes through a plurality of ports 65 (herein eight in number) in the plate 30. This additional air strikes a baffle plate 66 positioned in the upper portion of the flame chamber FC, so as to divert the air outwardly before it passes downwardly, and mixes with products of combustion in the flame chamber so as to be heated thereby and discharge therewith into the gasifying chamber GC.

The main fuel supply is discharged into the gasifying chamber GC and, as illustrated herein, passes through a jet 70 positioned in the upper end of the tube 26, through the tube 26 and through a connecting tube 71 extending through the flame chamber FC and down to the upper end of the gasifying chamber GC. The fuel upon entering the gasifying chamber mixes with the hot products of combustion and additional air entering the gasifying chamber through an annular passage 71' formed intermediate the tube 71 and the upper end of the tubular member 33.

The jet 70 at the upper end of the fuel tube 26 is provided with a plurality of horizontal ports 75 and a vertical air bleed port 76. When the invention is installed on the intake manifold of an internal combustion engine so that suction is applied to the lower end of the passage 14, the various chambers and passages in the fuel converter are also placed under suction. This is sufficient to raise the level of the fuel within an inverted cup-shaped member 77 which is positioned over the jet 70 and the upper end of the tubular portion 25 of the fuel bowl, so that the fuel passes through the horizontal port 75 and down through the discharge port of the jet and into the fuel tube 26. In passing over the upper

end of the fuel tube, a portion of this fuel enters the vertical ports 26' which communicate with the annular port 27 and thereby supplies the fuel necessary to maintain the flame in the flame chamber. The air bleed port 76 is preferably provided to prevent syphoning of the fuel when the engine is stopped.

In operation, it is contemplated that fuel will be supplied to the fuel bowl 12 from suitable storage tanks, the inlet of fuel to the bowl being controlled by a suitable valve 80 operated by a float 81. The float 81 is in the form of an annulus and carries a spider 81' having a central portion 81'' which engages the valve 80 and a plurality of apertures 82 through which fuel may flow directly from the inlet passage 80' to the space within the float 81 and immediately adjacent the intake to the jet 70. The valve 80, although provided with a conical end, has a squared intermediate section so as to serve as a guide and still provide a passage for fuel.

Preferably, means is provided for supplying two different fuels to the fuel bowl when the converter is intended for use in connection with heavier hydrocarbon fuel, such as fuel oils. In such cases it is generally desirable to start the operation of the converter on a lighter fuel such as gasoline. For this purpose and for the purpose of providing fuel to prime the converter, a two-fuel valve 83 is mounted on the cover 12''. This valve has a casing 83' provided with an inlet 84 adapted for connection to a supply of gasoline and an inlet 85 adapted for connection to a supply of fuel oil. A cylindrical valve element 83'' is operable by means of an arm 86 (Figs. 1, 9 and 10) and has three positions, in one of which (Fig. 1) it is adapted to supply gasoline to a priming means, in another of which (Figs. 9 and 10) it is adapted to supply gasoline to the intake port 80', and in a third of which it is adapted to feed fuel oil to the intake 80'. These positions of the valve are indicated by the letters G (for gasoline), P (for priming), and O (for oil), indicated in Fig. 10. Preferably a spring pressed detent device 87 (Fig. 9) is provided for maintaining the valve in its adjusted positions.

The valve element 83'' has three diametrical ports P', G' and O' extending therethrough. As shown in Fig. 1, the valve port P' establishes communication between the gasoline inlet 84 and a passageway 88 in the cover 12'' which communicates at one end with a port 89 in the valve casing 83' and at its other end with a tube 88' (Fig. 1) which extends downwardly and communicates at its lower end with a horizontal passage 110 in the body member 10, which in turn communicates with a discharge pipe 111 extending into the main passage 14 to discharge priming fluid into said passage. Preferably a jet 112 is inserted in the tube 88' to meter the fuel flowing to the discharge pipe 111. Also, for priming purposes, a jet 113 is connected to the tube 88' and discharges into the chamber 63 during a priming operation, this fuel flowing into the flame chamber FC through the openings 65.

The valve element 83'', when in the position marked G (Figs. 9 and 10) is adapted to feed gasoline from the inlet port 84 through a connecting port 115, valve port G', a port 116 in the valve casing, and inlet port 80' to the fuel bowl. In this position of the valve, the priming means and the oil supply are cut off by the rotation of the ports P' and O' out of vertical alignment with the inlet ports 84 and 85. To

feed oil from the inlet port 85 to the fuel bowl the valve element 83 is rotated to the position marked O (Fig. 10) in which position the port O' connects the inlet port 85 with a port 117 in the valve casing. This port connects with 5 the passage 118 communicating with the inlet port 80'. When the valve element is moved to feed oil to the fuel bowl, the gasoline supply both to the fuel bowl and to the priming means is disconnected.

The air valve of compensator 22 hereinbefore referred to is pivoted by means of a horizontal shaft 90 and has an arm 91, the outer end of which is secured by means of a pin 92 to the upper end of a rod 93. The lower end of the rod 93 15 engages an adjusting screw 94 threaded into the lower wall of a housing member 95 which surrounds the air valve mechanism. The adjusting screw is thus effective to determine the closed position of the air valve with respect to the seat 20 21. A tubular member 96 surrounds the lower portion of the rod 93 and is slidably mounted in a vertical bore 97 in the housing 95. This tubular member may be adjusted vertically by means of an arm 98 (Fig. 6) which is attached to a 25 shaft 99 rotatably mounted in an extension 95' of the housing 95 and carries a disk 100 (Fig. 1) on which an eccentric pin 101 is mounted. This pin engages in an annular groove 102 formed in the upper end of the tubular member 96 so that 30 by rotating the shaft 99 by means of the arm 98 the vertical position of the member 96 may be adjusted. This adjustment is utilized to vary the tension exerted on the air valve 22 by means of a coiled spring 103 which is positioned within 35 the tubular member 96 and intermediate a disk 104 (secured to the lower end of the rod 93) and a shoulder 105 formed on the upper end of the member 96. To minimize fluttering of the air valve, a weight 106 is preferably secured to the 40 rod 93 by means of a pin 107.

The operation of the invention will now be described on the assumption that the body member 10 is properly installed on the intake manifold of an internal combustion engine, and a 45 suitable fuel is supplied to the inlet ports 84 and 85 of the valve 83 so that the fuel bowl 12 is filled to its normal level, as indicated. Upon cranking the internal combustion engine, the lower portion of the passage 14 is subjected to 50 suction with the result that through the interconnecting passages, chambers and ports suction is applied on the main jet 70 sufficient to draw fuel upwardly through the annular space intermediate the member 17 and the fuel bowl portion 55 25. A portion of this fuel passes downwardly through the ports 26' through the annular port 27', horizontal port 45, vertical port 46 and jet 47 to the fuel tube 44. At the same time, air is drawn in through the diverting member 60, 60 ports 61 and 62, chamber 63, port 64, air tube 53, and chamber 54 to mix with the fuel in the chamber 51. This mixture passes upwardly through the ports 56, chamber 50' and burner tubes 43 and into the flame chamber FC where 65 the combustible mixture is ignited by means of a spark plug S (Fig. 5), the points of which project into the flame chamber. The products of combustion are first mixed with the additional air entering the flame chamber through the ports 70 65 and then pass through the annular passage 71' into the gasifying chamber GC wherein they are mixed with the main fuel fed through the jet 70 and tubes 27 and 71. Since the temperature of the inert gases from the flame chamber may 75

be around 2000° F. and the mixture of inert gases and additional air is also in the neighborhood of this temperature, the fuel discharged into the gasifying chamber is subjected to these 5 gases and air at such high temperature with the result that the lighter ends of the fuel are immediately vaporized, mixed with the hot air and burned and the resulting heat, added to the heat of the flame chamber gases, cracks the remainder 10 of the fuel and forms fixed gases. These pass on out through the passages 36, 37, 38, 39 and 40 during which passage they are cooled so that when they are discharged from the outlet 41 into the main passage 14 they are mixed with the 15 main volume of incoming air so that the resulting mixture passing the throttle 15 may be in the neighborhood of 140° F. This cooling is accomplished partly by the tortuous path through which they pass and additionally by radiating 20 vanes 11' on the converter casing 11.

Preferably, an aperture 72 is provided in the lower portion of the member 35 so that any fuel which may condense in the exit passages in the bowl 11 gravitates to the bottom of this bowl and 25 is returned through port 72 to the gasifying chamber. Such condensation may occur when the apparatus is started and has not reached its normal operating temperatures, the gases passing out from the gasifying chamber through the 30 cooling means (the bowl 11 being preferably formed of a material such as aluminum to increase its cooling capacity) having some portions of vapor mixed therewith which condense. Furthermore, any quantity of fuel collecting in 35 the bottom of the bowl 11 serves as an extra supply to take care of sudden load demands and improves the operation of the device when used on motor vehicles.

If the apparatus is started cold, the operation 40 may be instituted with the valve element 83" in its priming position wherein gasoline will be fed directly into the main passage 14 and into the flame chamber. As soon as the priming operation is completed, the valve element 83" is 45 shifted to the position of Fig. 9 wherein the more volatile of the two fuels is fed to the fuel bowl.

As soon as the converter has reached a stable 50 operating temperature, the valve 83" is shifted so as to feed the heavier hydrocarbon fuel to the fuel bowl and permit the conversion of such 55 heavier hydrocarbon fuel into fixed gases in the same manner as described for the lighter fuel.

During operation of the apparatus, the air valve or compensator 22 serves to close the main 55 passage 14 at idling speeds of the engine so as to increase the suction in the converter. As the speed of the engine increases and the volume of air passing therethrough becomes larger, the compensator 22 is swung on its pivot shaft 98 60 against the compression of the spring 103 so as to permit additional quantities of air to pass downwardly through the passage 14 and mix with the fixed gases discharged from the outlet 41. The amount of air passing through passage 14 at 65 idling speed may be adjusted by means of the screw device 94. Furthermore, if it is desired to choke the apparatus on starting, this may be accomplished by means of the control arm 98 (Fig. 6) which when rotated increases the compression of the spring 103 and thereby acts to 70 hold the compensator 22 more firmly in its low speed position. A port 15' in the valve 15 is preferably provided to function as an idling passage when the throttle is closed and enable suction to be applied to the converter.

It is believed readily apparent that the apparatus as disclosed herein is simple in form and compact in structure. The provision of a fuel bowl, fuel feeding means, and fuel supply means wherein either of two fuels may be discharged 5 into the fuel bowl and in proximity to the inlet to the fuel feeding means enables a quick change from one fuel to the other when the device is in operation. Thus, if the connection to the heavy fuel is left on when operation ceases and the 10 device has sufficiently cooled to make it desirable to use the lighter fuel for starting purposes, a switchover from the heavy to the light fuel gives a practically instantaneous supply of light fuel to the fuel feeding means.

The construction of the flame and gasifying chambers is also of particular advantage. As illustrated herein, the air supplied through tube 53 is heated in its passage through the tube and through the annular chamber 54 before it comes 20 in contact with the fuel passing through fuel tube 44, and the resulting mixture of hot air and vaporized fuel passes annularly through the chambers 51 and 58 so as to be thoroughly mixed and is heated before discharge from the burner 25 tubes 43. Furthermore, with the tubular member 33 positioned centrally in the cup-shaped member 31, a very compact arrangement is obtained, the thicker upper portion of the member 33 cooperating with the fuel tube 11 to form a 30 restricted passage 11' through which the hot inert gases and heated air pass into the gasifying chamber. The construction of these parts is such as to permit of ready replacement if after long 35 usage they are deteriorated due to the intense heat to which they are subjected. By removing the fuel bowl element, these inner parts become readily accessible and, if desired, the cup-shaped member 31, tubular member 33, and the annular plates 42, 58 and 52 may be supplied as a unit, 40 either with or without the air tube 53 and fuel tube 44. This permits of convenient assembly of the parts originally as well as replacement.

I claim as my invention:

1. A device of the character described comprising, in combination, a main body member having a downdraft passage therein and adapted at its lower end for connection to the intake manifold of an internal combustion engine, a fuel converter comprising a bowl-shaped casing secured to one side of said body member, a cover for said casing, a fuel bowl positioned above said cover, a float controlled valve in said fuel bowl, a flame chamber within said converter casing and substantially centrally thereof, means for feeding a mixture of fuel and air to said flame chamber including fuel and air tubes passing through the flame chamber, means forming a gasifying chamber, means forming an outlet from the flame chamber to the gasifying chamber, means for supplying additional air to the flame chamber independently of said fuel and air mixture so that the additional air intermixes with and is heated by the products of combustion before passing into the gasifying chamber, means for conducting fuel from said fuel bowl directly to said gasifying chamber, and means forming a passage from the gasifying chamber to the passage in said body member.

2. A fuel converter comprising, in combination, a bowl-shaped casing, a cover for said casing, a fuel bowl positioned above said cover, a float controlled valve in said fuel bowl, means forming a flame chamber within said converter casing and substantially centrally thereof, means for

feeding a mixture of fuel and air to said flame chamber, means forming a gasifying chamber in said converter casing below said flame chamber, means for conducting fuel and the products of combustion from the flame chamber to the gasifying chamber, additional means for supplying additional air to the flame chamber for mixture with the products of combustion prior to their discharge into the gasifying chamber so as to be heated thereby, and a discharge passage leading from said gasifying chamber.

3. In a device of the character described, in combination, a converter casing, means forming a gasifying chamber within said casing, means for supplying a mixture of hot inert gases and air to said gasifying chamber including means forming a port through which said products pass into the gasifying chamber, and means for discharging fuel into said gasifying chamber including a fuel tube, a fuel bowl into which one end of the fuel tube extends and means for connecting either of two fuel supplies to said fuel bowl comprising a valve device, and means for directing the fuel into the fuel bowl in the immediate vicinity of the end of the fuel tube.

4. A device of the character described comprising, in combination, a main body member and having a downdraft passage therethrough and adapted at its lower end for connection to the intake manifold of an internal combustion engine, a fuel converter comprising a casing secured to said body member and having a flame chamber and a gasifying chamber therein, means forming a first series of passages for supplying fuel and air to said flame chamber, and means forming a second series of passages for supplying fuel and air to said gasifying chamber, a fuel bowl positioned above said converter casing, a float control valve for maintaining the normal level of fuel in said fuel bowl, a valve device positioned above said fuel bowl and having two inlet ports, one for connection to a gasoline supply, and the other for connection to a heavier oil supply, and having a plurality of positions of operation, in one of which gasoline is supplied to said fuel bowl, and in another of which a heavier oil is supplied to the fuel bowl.

5. In apparatus for the conversion of liquid fuel, in combination, a casing comprising a flame chamber and a gasifying chamber below the flame chamber, passages for supplying a combustible mixture of fuel and air for maintaining a flame in the flame chamber, an additional passage for supplying excess air to the upper portion of the flame chamber, a tube communicably connecting the flame chamber with the gasifying chamber, means for admitting liquid fuel to the gasifying chamber, and means for cooling the products discharged from the gasifying chamber.

6. A device of the character described comprising, in combination, a main body member having a passage therein and adapted at one end for connection to the intake manifold of an internal combustion engine, a converter secured to one side of said body member and arranged to convert liquid fuel into fixed gases, a fuel bowl supported above said converter, a fuel feeding member having an inlet portion uprising from the bottom of the bowl to a position above the normal fuel level, an annular float device in said bowl surrounding the upper end of said member, and a valve operated by said device for maintaining the fuel level in said fuel bowl, said valve device controlling a fuel inlet port discharging directly into the space centrally of the float de-

vice and adjacent the inlet portion of the fuel feeding member.

7. In a device of the character described, in combination, a converter casing, a gasifying chamber formed within said casing, means for supplying a mixture of hot inert gases and air to said gasifying chamber including a flame chamber, a passage for supplying a combustible mixture of fuel and air to said flame chamber for combustion therein to form inert gases, a passage for supplying additional air to mix with said inert gases, and means forming an annular port through which said products pass into the gasifying chamber, and means for discharging fuel into said gasifying chamber including a fuel tube forming the inner wall of said annular port.

8. A device of the character described comprising, in combination, a main body member having a downdraft passage therethrough and adapted at its lower end for connection to the intake manifold of an internal combustion engine, a fuel converter comprising a casing secured to said body member and having a flame chamber and a gasifying chamber therein, means forming a first series of passages for supplying fuel and air to said flame chamber, and means forming a second series of passages for supplying fuel and hot air to said gasifying chamber, a fuel bowl positioned above said converter casing, a priming device, a float control valve for maintaining the normal level of fuel in said fuel bowl, a valve device positioned above said fuel bowl and having two inlet ports, one for connection to a gasoline supply, and the other for connection to a heavier oil supply, and having three positions of operation, in one of which gasoline is supplied to said priming device, in another of which gasoline is supplied to said fuel bowl, and in the third of which a heavier oil is supplied to the fuel bowl.

9. A device of the character described comprising, in combination, a main body member having a downdraft passage therein and adapted at its lower end for connection to the intake manifold of an internal combustion engine, a converter secured to one side of said body member and arranged to convert liquid fuel into fixed gases and including a pair of fuel tubes, one of which supplies fuel to be burned in the converter for creating hot inert gases, and the other of which supplies fuel in larger quantities for conversion into combustible gases, a fuel bowl supported above said converter, a tubular member uprising from the bottom thereof to a position above the normal fuel level, a float device for maintaining the fuel level in said fuel bowl, means extending downwardly in said tubular member and forming two fuel passages, and an inverted cup-shaped member surrounding the upper end of said member and extending downwardly to a position below the normal fuel level so as to provide an annular port through which fuel may pass to said fuel passages.

10. In a device of the character described, in combination, a fuel bowl having a tubular portion uprising from the bottom thereof to a position above the normal fuel level, a float device for maintaining the fuel level in said fuel bowl, a fuel tube extending downwardly in a bore in said tubular portion having an axial port forming one fuel passage and cooperating with the bore in said fuel bowl to form another fuel passage, a jet secured in the upper end of said fuel tube and discharging thereto and having a plurality of horizontal inlet ports located above the normal fuel level in the fuel bowl, an inverted cup-

shaped member enclosing said jet and extending downwardly around the tubular portion of the float bowl to a position below the normal fuel level therein so as to provide an annular port 5 through which fuel may pass to said jet, and a port connecting said annular fuel port with the space within said cup-shaped member above the normal fuel level and adapted to receive fuel raised into said cup-shaped member by the suction 10 within said fuel tube.

11. A device of the character described comprising, in combination, a main body member having a downdraft passage therein and adapted at its lower end for connection to the intake 15 manifold of an internal combustion engine, a fuel converter comprising a bowl-shaped casing secured to one side of said body member, a cover for said casing, a fuel bowl positioned above said cover, a float controlled valve in said fuel bowl, 20 a flame chamber within said converter casing and substantially centrally thereof, means for feeding a mixture of fuel and air to said flame chamber including fuel and air tubes passing through the flame chamber, a gasifying chamber 25 in said converter casing below said flame chamber, an outlet from the flame chamber to the gasifying chamber, a passage for supplying additional air to the flame chamber independently of said fuel and air mixture, means forming a 30 passage from the gasifying chamber to the passage in said body member, and means for supplying priming fuel to said flame chamber and said downdraft passage.

12. A fuel converter structure comprising, in combination, a cup-shaped member having an opening in the bottom thereof, a tubular member within said cup-shaped member and positioned with one end extending into said opening and forming a chamber, a plurality of annular flat plates positioned externally of said 35 tubular member and within said cup-shaped member and cooperating therewith to form a plurality of annular chambers, an air supply tube extending through apertures in said plates to

discharge air into the lowermost annular chamber, a fuel supply tube extending through apertures in certain of said plates to supply fuel to an intermediate annular chamber, said plates having openings therein establishing communication between said annular chambers and between the uppermost annular chamber and the upper portion of the cup-shaped member. 5

13. A fuel converter structure comprising, in combination, a cup-shaped member having an opening in the bottom thereof, a tubular member within said cup-shaped member and positioned with one end extending into said opening and forming a chamber, a plurality of annular plates positioned externally of said tubular member and within said cup-shaped member and cooperating therewith to form a plurality of annular parallel chambers, said plates having openings therein establishing communication between said annular chambers and between the uppermost annular chamber and the upper portion of the cup-shaped member. 15

14. In a device of the character described, a main body member having a passage therein adapted for connection to the intake manifold 25 of an internal combustion engine, and a fuel converter comprising a bowl shaped casing, a cup-shaped member within said casing providing a flame chamber in which fuel and air are burned to form an inert gas having a high temperature, means for feeding a mixture of fuel and air to said flame chamber including a fuel tube passing through said flame chamber so as to be heated by the flame chamber and an air tube passing through said flame chamber to be 30 heated by said flame chamber, a member terminating in a recess forming a gasifying chamber opening through the bottom of said cup-shaped member, a passage providing communication between the flame chamber and the gasifying 40 chamber, and a passage leading from said gasifying chamber to the passage in said body member.

ENOCH RECTOR.
